UNITED STATES PATENT OFFICE

2,551,095

FEEDING DEVICE FOR CIGARETTE-MAKING MACHINES

Paul Chaze, Le Kremlin-Bicetre, France

Application April 11, 1945, Serial No. 587,770
In France May 11, 1943Section 1, Public Law 690, August 8, 1946
Patent expires May 11, 1963

5 Claims. (Cl. 222—162)

1

In machines for making cigarettes by means of paper tubes, tobacco is delivered to the machine as follows: after a predetermined amount of tobacco has been introduced by hand into a slot, a recess or a gutter provided in the machine, it is then compressed or packed and the roll of tobacco is pushed into the paper tube by operating the mechanism of the machine. A machine of the aforesaid type has been described and claimed in my prior British Patent 464,948.

It will be understood that a rather delicate manual operation is required for feeding the machine with tobacco, and irregularities may occur so that the cigarettes can be unevenly filled.

It is an object of my invention to provide an improved machine which is free from the above drawback. According to this invention, a device for delivering predetermined amounts of tobacco to machines for making cigarettes of the type described, comprises a semi-cylindrical trough having a split bottom and held in a stationary position above the slot or gutter of the machine; a member adapted to play the part both of a scraper and a tobacco container is capable of swinging or pivoting in the trough. The scraper is made as a bottomless box adapted to be filled with tobacco, the latter being subjected to a pressure tending to push it through the slot in the trough. Then, upon each swinging movement of the scraper, a predetermined amount of tobacco passes through the trough slot into the gutter of the machine, where it is packed and driven out by the mechanism of said machine.

The pressure on the mass of tobacco in the hollow scraper may be produced by springs acting on a pushing member slidably mounted in the scraper, the springs being preferably arranged so as to hold the scraper in either of its end positions.

The following description with reference to the appended drawings given solely by way of example will show how this invention may be carried out.

Fig. 1 is a diagrammatic side view of the machine for making cigarettes in accordance with my prior British patent, said machine being provided with a device according to this invention.

Fig. 2 is a vertical longitudinal section of the feeding device shown on a large scale.

Fig. 3 is a plan view of the trough.

Fig. 4 is a cross section taken along line IV—IV on Fig. 3.

Fig. 5 is a plan view of the scraper and Fig. 6 is a cross section taken along line VI—VI on Fig. 5.

2

Fig. 7 is a plan view showing the pushing member positioned in the scraper, and Fig. 8 is a longitudinal section taken along line VIII—VIII on Fig. 7.

5 Figs. 9, 10 and 11 are diagrammatic views illustrating the operation of my device.

Figure 12 is a fragmentary view corresponding to Fig. 2 showing an adjustable slot.

In the example shown in Figs. 1 and 2, the machine for making cigarettes generally denoted by reference character 1, has a slot 3 in its upper horizontal wall 2 (Fig. 2); above slot 3 lies a slot 4 in a semi-cylindrical trough 5 which is shown on Figs. 3 and 4.

10 15 The trough is fast with a frame 6 the lower part of which is secured on the wall 2 of the machine by means of screws 7 or any other suitable means, and has two spaced apart parallel cheeks 8 provided with holes 9 wherein the hollow scraper 10 is journaled; the journals may be for instance screws, studs or the like.

The scraper is a bottomless box and the lower edges of its faces are shaped as semi-cylinders having the same radius as the trough, as shown 20 at 11 on Fig. 6.

25 30 Owing to this construction, the lower edges 11a of the scraper transverse faces i. e. faces which do not contact cheeks 8, are tangent with the inner surface of the trough. Engaging the hollow scraper 10, is a pushing member 12 (Figs. 7 and 8) the bottom 13 of which has two or more holes 14 providing an exit for air when pushing member 12 is driven into the hollow scraper 10.

35 Springs 15 are interposed between stationary pins or lugs 16 on cheeks 8, and lugs 17 on the upper part of pushing member 12.

The feeding device operates as follows, reference being had to diagrammatic Figs. 9 to 11: an amount of tobacco corresponding for instance to the content of a package or half a package of tobacco is placed within the scraper box 10 as shown at 18 on Fig. 2. The pushing member 12 is then introduced into the scraper box, its introduction and removal being very easy by reason of the operation of springs 15 when the pushing member is manipulated.

When the pushing member 12 is in its place, tobacco 18 is subjected to the vertical pressure illustrated by arrow F on Fig. 2, which tends to drive a small amount of tobacco through the slot 3.

50 55 Assuming that the scraper is in the position shown on Fig. 9, tobacco will be very simply fed by swinging the scraper from the position shown on Fig. 9 to the position shown on Fig. 10. During the swinging motion, the end 11a of the left

hand wall of the scraper pushes tobacco in the direction of arrow *f* (Fig. 9); as tobacco is in abutment against the right hand end of slot 3, said tobacco is thus expelled and a determined amount thereof will pass through said slot as shown at 18a on Fig. 10.

When the machine is provided below the slot 4, with a gutter having a stationary wall 19 lined by an extraction spoon 19a (bearing the reference character 17 in my prior British patent) while the other wall is a pushing member 20 (equivalent to the compression member 13 in said British patent), tobacco will be packed by moving the pushing member 20 in the direction of arrow *f* (Fig. 11), and for obtaining a complete cigarette it will be only necessary to drive the amount of packed tobacco as a cylindrical roll (as shown at 18b on Fig. 11) by means of a transverse push rod fast with spoon 19a into the cigarette paper tube.

When the amount of tobacco 18a is deemed insufficient, the scraper 10 may be swung again i. e. brought back from the position shown on Fig. 10 to the position shown on Fig. 9, so that the right hand edge 11a will push a new amount of tobacco in the direction reverse to that of arrow *f*, and cause it to pass through the slot 4.

From the foregoing statement, it will be seen that each swinging movement of the scraper causes delivery of a predetermined amount of tobacco, so that my device plays the part of a feed adjusting device.

It will be obvious that a device in accordance with this invention may be used with material other than tobacco.

As springs 15 are located on one side of the swinging axis of the scraper, in each one of the extreme positions of the latter, said scraper is efficiently held in its place in either of said extreme positions.

It should be understood that alterations may be brought in the device above described without departing from the scope of this invention. In particular as shown in Figure 12, the slot 4 may have a variable width for instance by providing a slidable plate 21 occupying an adjustable position between the wall 2 of the machine and trough 5 and secured by bolts 22 passing through elongated slots 23 of plate 21.

What I claim is:

1. A feeding device of the type described which comprises a trough including spaced apart side cheeks and an intermediate semi-cylindrical member having a longitudinal bottom aperture: an open-ended box in the form of a parallelepiped cut across at its lower part by a cylinder of the same radius as said intermediate member and placed so as to be tangent through its bottom face with said intermediate member, the box being accommodated between the cheeks and journaled therein so as to be capable of swinging on an axis which is coincident with the axis of said semi-cylindrical member, a plunger fitted in and slidably engaging said box, and spring means between the top exposed portion of said plunger and said cheeks for biasing the plunger downwardly.

2. A feeding device of the type described which comprises a frame, a concave member having a delivery aperture secured on the frame, a tubular

hollow body having curved edges at one end, said curved edges being in contact with the inner surface of said concave member, a piston in said tubular hollow body for pushing material therein towards said concave member, and means providing a swinging axis for said tubular hollow body, said tubular hollow body being adapted to move with its edges in permanent contact with said concave member.

3. A feeding device of the type described which comprises a trough including spaced apart side cheeks and an intermediate concave member having a longitudinal aperture, a tubular hollow body pivotally mounted in the cheeks of said trough having its edges at one end adapted and arranged for contact with the concave member of the trough, and a plunger slidably mounted in the tubular hollow body for pressing any material towards said open end.
4. A feeding device of the type described which comprises a trough including spaced apart side cheeks and an intermediate concave member having a longitudinal aperture, a tubular hollow body having trunnions pivotally mounted in the cheeks of said trough having at one of its ends curved edges adapted and arranged for contact with the inner surface of the concave member of said trough, a plunger slidably mounted in and projecting from said tubular hollow body and resilient means operatively interposed between said plunger on its portion outside said tubular hollow body and said trough, for biasing said plunger towards said aperture.

5. A feeding device of the type described which comprises a trough including spaced apart side cheeks and an intermediate concave member having a longitudinal aperture, a tubular hollow body having trunnions pivotally mounted in the cheeks of said trough having at one of its ends curved edges adapted and arranged for contact with the inner surface of the concave member of said trough, a plunger slidably mounted in and projecting from said tubular hollow body and resilient means secured at least at one point of said plunger on its portion outside the tubular hollow body and at least at one outside point of said trough, said latter point being straight below said trunnions whereby the plunger is urged towards the trough and the hollow body is urged towards its extreme positions.
